UNITED STATES PATENT OFFICE.

JOSEPH SELL, OF RUSHCENTER, KANSAS.

HEATING MEANS FOR INCUBATORS.

1,277,266.

Specification of Letters Patent. Patented Aug. 27, 1918.

Application filed August 19, 1915. Serial No. 46,295.

To all whom it may concern:

Be it known that I, JOSEPH SELL, a citizen of the United States, residing at Rushcenter, in the county of Rush, State of Kansas, have invented a new and useful Heating Means for Incubators; and I do hereby declare the following to be a full, clear, and exact description of the invention, such as will enable others skilled in the art to which it appertains to make and use the same.

This invention relates to improved heating means for incubators, and an object of the invention is to provide a cylindrical member extending through an incubator, and into which member the heat is projected, there being a heater or lamp below the cylindrical member and extending thereto, in combination with a damper over the cylindrical member, which is automatically regulated by the heat in the incubator, owing to the heat acting upon a thermostatic device in the incubator.

Another object of the invention is to provide means for adjusting the lamp or heater, so that more or less of the heat may be projected into the cylindrical member.

Another object of the invention is the provision of a water container adjacent the cylindrical member, so as to render the heat in the incubator moist instead of dry.

Another object of the invention is to provide the lower part of the water container with the drain cock or faucet, for draining the water container.

In practical fields the details of construction may necessitate alterations, falling within the scope of what is claimed.

The invention comprises further features and combination of parts, as hereinafter set forth, shown in the drawings and claimed.

In the drawings:—

Figure 1 is a vertical sectional view through an incubator, showing the improved heating means applied thereto.

Fig. 2 is a sectional view on line 2—2 of Fig. 1.

Fig. 3 is a detail perspective view of an angular bracket, showing the lamp holder or support adjustably mounted thereon.

Fig. 4 is a plan view of the holder or support for the lamp or heater, showing the slotted arm of the angular bracket in section.

Referring to the drawings 1 designates a conventional form of incubator having a chamber 2 for the eggs, and supported upon

the legs 3, there being a closure 4 hinged at 5 and having a latch at 6, whereby access may be had to the chamber 2. Extending through the chamber 2 is a cylindrical member 7 forming a heating chamber 8. The flange 9 at the upper end of the member 7 prevents downward movement of the member. A circular ring 10 is threaded at 11 to the lower end of the cylindrical member 7, so that the part 12 of said ring engaging the bottom of the incubator will prevent upward movement of the cylindrical member 7. Secured at 13 to the bottom of the incubator is an angular bracket 14 having a downwardly extending slotted arm 15. A lamp holder or support consisting of an annular ring 17 and a bracket part 18 is provided. The bracket part has an elongated tongue 19, which fits into the slot of the arm 15, there being a plate 20 secured by screws 21 (which pass through the slots of the arm 15 and into the tongue 19) to the bracket part 18, with the arm 15 between the plate 20 and said bracket part 18. It is to be observed that by loosening the screws 21, the support 16 may be raised and lowered. By lowering the support 16 toward the lower part of the arm 15, the upper portion or top of the lamp or heater 22 is arranged below the cylindrical member 7, thereby decreasing the heating effect of the lamp. Riveted at 23 to the side of the cylindrical member 7 is a water container 24 constructed of any suitable material having a conical bottom 25 and a contracted extension 26 provided with an outlet orifice 27. The contracted extension has a transversely disposed drain cock or valve 28, for drawing off the water in said container. In the walls of the cylindrical member 7 and the container are registering openings 29, so that some of the heat may pass into the container, to assist in heating the water, which is also heated owing to the container being secured to the side of the cylindrical member 7. Pivoted to a post on the top of the incubator, as at 30, is a lever 31 having a damper 32, coöperating with the upper open end of the cylindrical member 7. When the damper 32 is in contact with the flange 9 of the cylindrical member 7 the heat is confined in the cylindrical member 7, excepting that which passes through the openings 29 into the water container, thereby keeping the container and the water therein well heated. Pivoted at 33 to a second post on top of the incubator

tor is a lever 34, one end of which is pivoted at 35 to the short arm of the lever 31, the other end of the lever 34 being pivoted at 36 to a link 37, which in turn is connected to 5 a thermostat at 38; supported on a bracket 39 inside the chamber 2 of the incubator. When the temperature in the chamber 2 rises to a certain degree this thermostat expands, lifting the damper 32, thereby decreasing the heating effect, and as the thermostat 38 contracts, owing to the temperature decreasing in the chamber 2, the damper 32 will close, thereby maintaining the temperature in the chamber 2 substantially uniform.

The invention having been set forth, what is claimed as new and useful is:—

In an incubator having an incubator chamber, a heating apparatus comprising a 20 water container arranged vertically centrally in said chamber and having its upper and lower ends connected in the upper and lower walls of said chamber, said container having its upper end open and its 25 lower end provided with draining means, an air heating tube having its upper and lower ends open, said upper and lower ends of said tube projecting through the upper and lower walls of said chamber, the upper end of said 30 heating tube having a flange coöperating

with the upper wall of the chamber, means for detachably connecting the lower end of the heating tube to the lower wall of the incubator chamber, the wall of the tube being in contact with the wall of the water 35 container, both the container and the heating tube being removable, said adjacent walls of the tube and container having registering openings substantially midway their contacting surfaces, whereby the heat 40 from said tube may pass through said openings into the container and over the surface of the water, a heating element adjustably supported below said chamber, for adjustment into said air heating tube, and automatic means coöperating with the upper open end of said air heating tube for controlling the heat from the heating element, whereby the heated air may be allowed to escape from the upper end of the tube or 50 caused to pass through said openings and over the surface of the water in the container.

In testimony whereof I have signed my name to this specification in the presence of 55 two subscribing witnesses.

JOSEPH SELL.
